UNITED STATES PATENT OFFICE.

CHARLES BLUME, OF CHICAGO, ILLINOIS.

BROW-BAND-ATTACHING DEVICE.

SPECIFICATION forming part of Letters Patent No. 645,449, dated March 13, 1900.

Application filed April 5, 1899. Serial No. 711,777. (No model.)

To all whom it may concern:

Be it known that I, CHARLES BLUME, a citizen of the United States, residing at Chicago, in the county of Cook and State of Illinois, 5 have invented certain new and useful Improvements in Brow-Band-Attaching Devices, of which the following is a specification.

This invention relates to improvements in the means of securing brow-bands on bridles 10 for horses; and it consists in certain peculiarities of the construction, novel arrangement, and operation of the parts thereof, as will be hereinafter more fully set forth and specifically claimed.

15 The objects of my invention are, first, to provide an attaching device for brow-bands which shall be simple and inexpensive in construction, strong, and durable, yet attractive in appearance; second, to afford an attaching 20 device for brow-bands which shall dispense with the necessity of forming loops thereon through which the throat and cheek billets or straps of the bridle are passed, as in the ordinary construction, and also obviate the necessity of sewing or stitching the same, thus 25 economizing in the amount of material and labor used in producing the bridle, and, third, to provide a means for securing the brow-band in position in such a manner that it will 30 afford no discomfort to the horse and will retain the band in its proper position.

In order to enable others skilled in the art 35 to which my invention pertains to make and use the same, I will now proceed to describe it, referring to the accompanying drawings, in which—

Figure 1 is a perspective view of the upper portion of a bridle, showing my attaching device for the brow-band secured thereto. Fig. 40 2 is a detached perspective view of one of the rosettes or devices. Fig. 3 is a perspective view of a portion of one end of the brow-band. Similar letters refer to like parts throughout the different views of the drawings.

45 A represents the crown-piece of a bridle, which is provided with cheek and throat billets or straps *a* and *a'*, respectively. As shown in Fig. 1 of the drawings, these straps or billets are produced by splitting the lower ends 50 of the crown-piece and are preferably made integral therewith; but they may be separate

straps secured thereto by stitches or otherwise. Secured to the crown-piece A is a brow-band B, of any suitable pattern and material, which has near each of its ends a longitudinal slot *b*, whose ends preferably terminate in circular openings *b'* to prevent the lengthening of the slot or splitting of the leather or material of which the brow-band is composed. To one side of each of these slots and at about 55 the middle thereof the brow-band is provided with an opening *b*², which communicates with the slots to receive the central projection or projections of the rosette C or attaching device, which is preferably of the construction 60 shown in Fig. 2 of the drawings, which consists of a rosette or body C, made of any suitable size, form, and material, but preferably of metal, and having on its surface adjacent to the crown-piece a loop *c*, which is provided 65 with a central projection *c'*, which divides the loop into two parts, one to receive the cheek billet or strap *a* and the other the throat billet or strap *a'*, as is clearly shown in Fig. 1 of 70 the drawings.

75 By reference to Fig. 2 of the drawings it will be seen and clearly understood that the central projection *c'* of the attaching device is flattened or widened for the purpose of preventing the hanging down of the brow-band. 80

By passing the loop or loops through the slot of the brow-band it is apparent that the central projection *c'* will fit in the opening *b*² at the middle of the said slot, when the straps *a* and *a'* may be passed through the loop, one 85 on each side of the said central projection, thus firmly securing the brow-band and crown-piece together.

Having thus fully described my invention, what I claim as new, and desire to secure by 90 Letters Patent, is—

1. As an improved article of manufacture, an attaching device for brow-bands, comprising a disk or plate, having a securing device, projecting from one of its sides, and a dividing portion extending from the disk intermediate the legs of the securing device, and extended laterally therefrom, substantially as described.

2. In a brow-band-attaching device, the 100 combination with a disk or plate having a securing device projecting from one side there-

of, of a dividing portion projecting from the disk or plate and intermediate the legs of the securing device and extended laterally therefrom, a brow-band having a slot and opening 5 to receive the securing device and the said dividing part, and a crown-piece provided with two straps or billets located in the se-

curing device, one of said straps on each side of the dividing part of said securing device, substantially as described.

CHARLES BLUME.
